MEANS FOR TREATING YARN

Robert F. Craig, Stanley, N. C.

Application May 11, 1936, Serial No. 79,104

2 Claims. (Cl. 91—51)

This invention relates to a winding machine and more especially to waxing means associated with said machine.

It is an object of this invention to provide in 5 a winding machine for winding cones of yarn on opposed sides thereof a waxing attachment over which the yarn travels as it is being wound, said waxing attachment being located longitudinally and centrally of said winding machine so as to 10 wax the strands from both sides of the winding machine.

Some of the objects of the invention having been stated, other objects will appear as the description proceeds when taken in connection with 15 the accompanying drawings, in which—

Figure 1 is a side elevation of one end of a winding machine showing the invention applied thereto;

Figure 2 is a top plan view showing the upper 20 portion of Figure 1;

Figure 3 is a transverse vertical sectional view taken along the line 3—3 in Figure 1;

Figure 4 is a vertical sectional detail view taken along the line 4—4 in Figure 1.

25 Referring more specifically to the drawings: The winder has suitable supporting frames such as 100 which have secured thereto bearings such as 101, said bearings having mounted therein a longitudinally disposed shaft 102. Secured at 30 spaced intervals on shaft 102 are yarn package supports 103 containing packages of yarn 104. A strand of yarn 105 is wound from the package 104 and leads upwardly through a conventional tension device 106. From this point the strand 35 105 leads through a suitable eyelet 107 and then laterally of the machine around a post 108. The direction of travel of the yarn is then reversed from whence it passes directly over the top of waxing roll 109 where the wax is applied to the 40 strand. This waxing roll is secured to a shaft 110, said shaft 110 being rotatably mounted in a trough 111, which contains a liquid wax. This trough is secured to upright longitudinal member 112 by any suitable means such as brackets 45 113. The member 112 rests directly on top of creel boards 114 which, in turn, are supported at their ends by suitable frames such as 100.

The boards 114 support the L-shaped members 115, the upright leg of said members having eyelets therein through which the yarn is adapted to 50 pass. After the strand of yarn 105 passes upwardly through the tension device 106, it then passes through the eyelet 107, around the post 108 and again in the opposite direction over the top 55 of roll 109. Then the strand passes through an-

other eyelet 117 which is similar to the eyelet 107 located in L-shaped member 115. Strand 105 then leads downwardly beneath the thread guide 119 and thence upwardly through traverse mechanism 120 and onto the cone of yarn 121. It will be noted in this form of winder, that the roll 121 is driven by frictional contact with the driving roll 122, therefore, it is seen that the surface speed of the cone is uniform at all times.

Likewise, in this form the trough 111 has a 10 heating element 124 which comprises a suitable resistance wire 125 through which current is adapted to pass and while doing so creates heat for melting the wax which is disposed within the trough 111.

15 Posts 108 are secured in horizontal flange portions of trough 111, and are made adjustable therein since set screws 108a penetrate suitable slots 108b and have their ends threadably secured within the posts 108. By providing these slots, 20 it is possible to vary the position of the posts 108 thereby enabling one to change the angularity of the strands 105 with respect to the roll 109 to thereby vary the amount of wax applied to the strands. It will be further noted that strands 25 105, after they leave the eyelets 107 and when they pass around posts 108, do not touch the upper side of the roll, but on their travel from the posts 108 to the eyelets 117, there is a peripheral contact with the roll 108 and it is at this point 30 that the wax is applied.

The shaft 110 has a suitable driving wheel 126 fixedly secured on the end thereof, said driving wheel having a belt 127 mounted thereon. This belt is also mounted on another pulley 128 which 35 is fixedly secured on main drive shaft 129 of the winding machine.

One side of the machine has been described in detail, and since the opposite side is identical except that it is reversed, a description of this 40 side will not be repeated, but like parts will be given like reference characters with the prime notation added.

It is therefore, seen that I have provided a 45 common waxing means for accommodating strands drawn from opposed sides of a winding machine for waxing the same.

In the drawings and specification there has 50 been set forth a preferred embodiment of the invention, and although specific terms are employed, they are used in a generic and descriptive sense only, and not for purposes of limitation, the scope of the invention being set forth in the appended claims.

I claim:

1. In a machine for winding yarn into packages and having a plurality of spindles on each side of the machine onto which yarn is adapted to be wound, a waxing trough on top of the machine, a roller in said trough driven by the machine, and means for guiding the yarn from both sides of the machine across and in contact with said roller before it is wound onto the spindles.

2. In a winding machine for yarn having spindles on each side of said machine for receiving yarn, a waxing trough disposed on the upper central portion of the machine having a driven roller therein, means for guiding the yarn from both sides of the machine across said roller in wiping contact therewith before the yarn reaches the spindles on both sides of the machine.

ROBERT F. CRAIG.
